(57) **CLAIM**

The ornamental design for a home plate key chain, as shown and described.

DESCRIPTION

FIG. 1 is a front perspective view of a home plate key chain;
FIG. 2 is a top view thereof;
FIG. 3 is a bottom view thereof;
FIG. 4 is a rear view thereof;
FIG. 5 is a right side view thereof; the view from the opposite side being a mirror image;
FIG. 6 is a front perspective view of a second embodiment of the home plate key chain;
FIG. 7 is a top view of the second embodiment;
FIG. 8 is a bottom view of the second embodiment;
FIG. 9 is a rear view of the second embodiment; and,
FIG. 10 is a right side view of the second embodiment; the view from the opposite side being identical.
